R. D. BUELL

ALARM OR SIGNAL DEVICE

Filed Dec. 30, 1921

Inventor:
ROY D. BUELL
Emery, Booth, Janney & Varney
Atty's

UNITED STATES PATENT OFFICE.

ROY D. BUELL, OF CHICAGO, ILLINOIS.

ALARM OR SIGNAL DEVICE.

Application filed December 30, 1921. Serial No. 526,025.

To all whom it may concern:

Be it known that I, ROY D. BUELL, a citizen of the United States, and a resident of Chicago, Illinois, have invented an Improvement in Alarm or Signal Devices, of which the following is a specification.

This invention relates to sound producing devices and particularly to that class wherein the actuating force consists of pressure fluid such as is produced, for example, in internal combustion engines.

Among other objects, the invention is intended to provide a device which is practical, of simple construction and cheap to manufacture.

One embodiment of the invention for accomplishing these and other objects is shown for illustration in the accompanying drawings in which—

Fig. 1 is fragmentary side elevation of a portion of an automobile illustrating one application of the invention, and showing an internal combustion engine associated therewith and typifying a source of pressure fluid for actuating the device.

Fig. 2 is a sectional elevation taken approximately as indicated by the line 2—2 of Fig. 3.

Fig. 3 is a plan section taken on the line 3—3 of Fig. 2.

In the illustrative arrangement, relatively adjustable sound producing means are actuated by pressure fluid applied directly thereto, and certain of said means are adjustable with respect to the applied pressure fluid.

Referring to the drawings, a frame or housing 5 is secured to the front side of the dash-board 6 and under the hood 7 of an automobile.

Secured to the front open end of said housing is a horn or resonator 8 and between said housing and resonator is mounted a vibratory diaphragm 9, having secured thereto at, or near, its central portion a wear-piece 10.

To vibrate the diaphragm, a toothed wheel or rotor 11 of relatively heavy or weighted construction is mounted in said housing and is provided with a plurality of teeth 12 cooperable with said wear-piece.

To actuate said rotor, the housing 5 is provided with an opening 13 for receiving a fluid jet or nozzle 14 on one end of a conduit 15 through which pressure fluid is admitted.

The opposite end of said conduit is connected to a manually controlled valve mechanism 16 of any suitable type, associated with any source of pressure fluid supply such, for example, as an internal combustion engine 17, in which case, the valve mechanism may be positioned in a screw-threaded opening in the head of the engine usually occupied by one of the pet-cocks or priming cups 18.

The jet or nozzle 14 is positioned substantially tangential to the path of movement of the teeth on the rotor, and when pressure fluid is directed against the substantially radial faces of the teeth, the rotor will be driven to bring, successively, the opposite or cam faces of the teeth 12 into engagement with the wear-piece 10 on the diaphragm 9.

After the flow of fluid is discontinued, the heavy or weighted construction of the toothed wheel or rotor will have the effect of a fly-wheel to continue the rotation of said wheel, thus permitting a gradual reduction of the speed of the latter and consequently a like reduction in the vibrations of the diaphragm, thereby producing a more pleasing sound than as though the rotor stopped abruptly with the cessation of the flow of fluid.

To utilize to the fullest possible extent the pressure fluid for driving the rotor, the substantially radial faces of the teeth 12 are provided with cup-like depressions 19 so formed and positioned with respect to the jet 14 as to receive and prevent, temporarily, the escape of the fluid laterally therefrom, while the opposite or cam faces of the teeth are provided with grooves 20 to permit free passage of the pressure fluid to the cup-like depressions on the preceding teeth.

To properly position the teeth of the rotor with respect to the jet or nozzle 14, a pair of oppositely disposed adjusting screws 21 may be screw-threaded into the walls of the housing 5 and have their inner ends cupped to receive an anti-friction connection for supporting the rotor as, for example, the outer sides of balls 22, the opposite sides of which enter the depressions 23 formed in opposite sides of the rotor.

Thus, it will be observed that by screwing up one of the adjusting screws and backing away the other, the rotor may be positioned to bring the cup-like depressions 19 of the teeth 12 into proper alignment with the

jet or nozzle 14, and be secured in such position by the lock-nuts 23 on the adjusting screws.

To properly position the diaphragm 9 with respect to the teeth of the rotor and to compensate for wear of the piece 10, an adjusting screw 24 may be screw-threaded into the flaring portion of the housing 5 in a manner to engage the diaphragm within its circumference, and by manipulating said adjusting screw, the diaphragm together with the wear-piece may be moved away from or permitted to approach said teeth as desired, the screw 24 being secured in adjusted position by the lock-nuts 25.

For convenience in controlling the operation of the device, a cable or rod 26 operatively connected at one end to a valve actuating lever 27 may be passed rearwardly through the dash-board 6 and have secured to its opposite end a handle or button 28 positioned within easy reach of the driver.

In the operation of the device, a pull exerted on the cable or rod 26 will cause the lever 27 to open the valve thereby permitting a flow of pressure fluid to pass through the jet or nozzle 14 and be directed against the substantially radial faces of the teeth of the rotor.

30 The direction of fluid flow being on a line substantially tangential to the path of movement of said teeth, and a substantial distance from the center of the rotor, will impart to the latter a rotary motion, thus causing the teeth 12 to successively impinge the wear-piece 10, thereby producing a rapid vibration of the diaphragm.

An outlet port 29 is provided in the housing 5 to permit the escape of the fluid after 40 it has performed its rotor-driving function.

Obviously, the present invention is not limited to the precise details of the illustrative device, but may be variously modified. Moreover, it is not essential that all 45 the features of the invention be used conjointly; as they may be used to advantage in variously different combinations and sub-combinations.

I claim:

50 1. In a device of the character described, a housing; a diaphragm mounted therein; a rotor having axial depressions; oppositely disposed adjusting means mounted in said housing; means cooperable with said adjusting means and said depressions for supporting said rotor; a pressure fluid jet mounted in said housing; a plurality of teeth associated with said rotor for vibrating said diaphragm and provided on one face with cup-like depressions for receiving fluid from said jet, and on the opposite face with grooves for permitting the unobstructed passage of said fluid to said cup-like depressions; and means for adjusting said diaphragm with respect to said teeth.

55 2. In a device of the character described, a housing; a diaphragm having a wear-piece and mounted in said housing; an imperforate rotor; oppositely disposed adjustable projections adapted to axially engage said rotor to support the latter; a plurality of teeth on said rotor and cooperable with said wear-piece to vibrate said diaphragm; a jet for directing pressure fluid against said teeth; and means for adjusting 70 said diaphragm with respect to said teeth.

3. In a device of the character described, a housing; a diaphragm mounted therein; a fluid actuated rotor adjustably mounted in said housing and having teeth cooperable with said diaphragm to vibrate the latter, said teeth having means associated therewith for receiving and holding said fluid and means for permitting the free passage of said fluid to said receiving and holding means; means for directing pressure fluid against said teeth for actuating said rotor; means mounted in said housing for adjusting said rotor with respect to said directing means; and means outside said housing for adjusting said diaphragm with respect to said rotor.

4. In a device of the character described, a diaphragm having a resonator associated therewith; a fluid actuated rotor having teeth cooperable with said diaphragm; means for directing pressure fluid against said teeth for rotatably actuating said rotor to vibrate said diaphragm; means for adjusting said rotor and teeth with respect to said directing means; means for controlling the flow of fluid to said teeth; and means for continuing the rotation of said rotor after the flow of fluid is discontinued.

5. In a device of the character described, a vibratory diaphragm having a resonator associated therewith; a fluid actuated rotor having teeth cooperable with said diaphragm to vibrate the latter; a fluid nozzle associated with said teeth; means for adjusting said rotor and teeth with respect to said nozzle; and means for adjusting said diaphragm with respect to said teeth.

6. A device of the character described comprising, in combination, a resonator having a diaphragm associated therewith, a fluid-actuated rotor having teeth cooperable with said diaphragm to agitate the latter; a fluid nozzle associated with said rotor and means for adjusting said rotor with respect to said nozzle.

7. In an alarm or signalling device, the combination of a diaphragm; a toothed rotor for vibrating said diaphragm and adapted to be driven by impulses from a pressure fluid engine, said rotor being weighted for continuing the movement thereof after said impulses are discontinued; means for directing said impulses against the teeth of said rotor; and means for ad-

justing said rotor with respect to said directing means.

8. In a device of the character described, a housing; a vibratory diaphragm mounted therein; a toothed rotor cooperable with said diaphragm and having oppositely disposed axial depressions; fluid directing means cooperable with said rotor; anti-friction means cooperable with said depressions for supporting the rotor and means for holding said anti-friction means in rotor-supporting position.

9. In a device of the character described, a housing; a vibratory diaphragm mounted therein; a toothed rotor cooperable with said diaphragm and having oppositely disposed cup-like depressions positioned axially

thereof; fluid directing means cooperable with said rotor; spherically formed anti-friction elements cooperable, on their inner sides, with said depressions for supporting the rotor; and oppositely disposed longitudinally adjustable projections mounted in the walls of the housing and provided, at their inner ends, with cup-like concavities for engaging the opposite sides of said spherically formed elements for supporting said rotor within said housing.

In testimony whereof, I have signed my name to this specification.

ROY D. BUELL.
